CLAIM

The ornamental design for tables for a planer, as shown and described.

DESCRIPTION

FIG. 1 is a left side perspective view from the front of tables for a planer showing my new design;

FIG. 2 is a top plan view of my new design;

FIG. 3 is a back elevational view of my new design;

FIG. 4 is a front elevational view of my new design;

FIG. 5 is a right elevational view of my new design; and,

FIG. 6 is a left elevational view of my new design.

In the attached drawings, any broken line illustration is not part of the design sought to be patented.
